OIL BURNING HEATER

Boyd F. Castle, Henry Lange, and Frederick G. Suchland, Quincy, Ill., assignors to The Quincy Stove Manufacturing Company, Quincy, Ill., a corporation of Illinois

Application June 7, 1940, Serial No. 339,236

12 Claims. (Cl. 158—91)

This invention relates to an oil burning heater having a concentric burner with a central inspirating air inlet.

In many oil burning heaters, air is admitted at the outside which has a tendency to centralize and concentrate the heat and burning gases so that the greatest heating efficiency is not obtained. In the present invention this objection is overcome by providing the air inlet in the form of an inspirator at the center of the burner, causing the path of the flames and the products of combustion to pass from the center outwardly to produce an outwardly flaring and spiral movement of the gases, thereby tending to throw them in contact with the outer wall or drum of the heater for quickly producing the desirable heating effect.

Important objects of the invention are: to provide an improved central inspirating structure for causing an outward movement of the products of combustion; to provide an improved inspirating burner with a central air inlet for low flame burning conditions; to provide a central inspirating burner with parallel perforated shells in which the corresponding perforations are axially aligned and proportioned to obtain the proper gas-to-air mixture; to utilize a central inspirating air burner for throwing flames and products of combustion outwardly for quickly and thoroughly heating the outer wall surfaces; and in general to produce the structure herein shown and described.

In the accompanying drawing illustrating preferred embodiments of the invention,

Fig. 1 is a sectional view of an oil burning heater in accordance with the invention;

Fig. 2 is a detail section showing a modification of the burner heat deflecting surface made of a plastic material; and

Fig. 3 is a sectional view of the burner showing the inspirational openings in proper alignment to produce the proper mixing of primary air.

Referring now more particularly to the drawing, a heating drum 10 of suitable sheet metal is loosely enclosed in an outer casing 11 with an air space between them all around the sides and top. A discharge flue or pipe 12 extends from the drum near the top thereof through the casing and in the drum below the pipe 12 are baffles 13, having a number of openings 14 about the edge at a distance from the flue pipe and 15 having a central opening 16 out of a line with the openings 13. Any suitable means may be provided in the casing or leading from the casing for dis-

tributing the heat which is given off by the drum due to the operation of the burner.

The burner comprises a receptacle 17 having a central opening 18 at the bottom and an outwardly extending upper rim 19 with a flanged edge 20 secured to the inner wall of the drum by any suitable fastening means 21 and the wall of the receptacle being spaced from the inner wall of the drum by the rim 19.

Seated within the receptacle and extending upwardly from the central opening 18 is an inspirator comprising an inner sleeve 22 which substantially fits the opening 18 and a surrounding shell 23 spaced from the sleeve to provide a ring-shaped cylindrical mixing chamber 24 closed at the top and the shell held in spaced relation by a ring 25 located below the top of the sleeve 22.

The bottom edge of the shell is above the bottom of the pot a sufficient distance to permit the vaporized gases to enter the mixing space 24, providing free communication from the bottom of the receptacle with the annular mixing chamber 24. Located in the sleeve and shell are a number of rows of corresponding aligned holes or openings 27 and 28 which constitute inspirators for air from within the sleeve 22 across the mixing chamber 24 and outwardly through the openings in the shell. The openings or perforations in the outer shell are preferably larger than the corresponding aligned openings 27 in the inner sleeve 22. At the top of the sleeve which projects above the ring 25 is another row of openings 29, and the top of the sleeve is closed by a cap or top plate 30 which extends outwardly to approximately the same extent as the shell 23 so that the openings 29 admit secondary air at the top of the burner which is deflected outwardly by the projecting edge of the top plate and materially aids in completing the combustion and effects the clean and clear burning of the fuel by the burner.

For low heat and maintaining a minimum fire in the burner, a flange 31 is secured to the outer shell at a point above the lower row of holes 28, and an outer wall or deflector 32 may be positioned within the receptacle, preferably having a lower straight rim placed in alignment with the flange 31 and leaving a narrow annular space or neck 34 through which the gases and products of combustion may pass. The deflector then rounds outwardly and upwardly to the upper edge of the receptacle, forming a flaring bowl in which combustion takes place, the walls diverting the flames and gases upwardly and outwardly.

where they contact with the walls of the drum 18.

If desired a restraining ring 35 may be seated upon the rim 18, and projecting inwardly therefrom, to deflect the flames and products of combustion from the lower walls of the drum directly above the heater.

Fuel is admitted to the annular bottom of the receptacle through a pipe 36 which extends through openings in the lower wall of the drum and of the casing surrounding it.

At the bottom of the drum below the burner is a baffle plate 37 having a number of openings 38 preferably adjacent the periphery so that air entering them from the bottom of the drum will sweep over the bottom of the receptacle, tending to cool it. If the casing 11 is seated directly upon the floor or other support, openings are left for the air to enter at the bottom of the drum, and if the receptacle is raised upon legs or supports 39 the air will enter freely at the bottom of the drum, the drum being suitably supported in the casing 11 as by angle iron braces or supports 40.

Instead of the heat deflector 32 being made of metal it may be composed of a plastic heat resisting material such as firebrick and if desired a unitary or sectional firepot of this material 41 may be substituted for the upper wall of a receptacle as shown in Fig. 2, in which the receptacle is shown with a short outer wall 43 terminating in the flange 19 at about the level of the flange 31 so that the lower edge 44 of the plastic material 41 is supported on the rim 18 providing a reduced ring-shaped neck or opening 45 for the low heat condition above the lower ring of openings 28.

In the operation of the above described device oil is delivered to the bottom of the receptacle or pot 17 in regulated quantity. Assuming the oil to have been ignited as by torch, match or burning oil-soaked waste, flowing oil will be vaporized to form oil gas.

The air flowing into the receptacle through the relatively small apertures 27 and the aligned relatively large apertures 28 produces an aspirating effect or injector action which induces the flow of fuel gas into the mixing chamber 24 where it is mixed with the aspirating air and then injected into the receptacle or retort where it is burned.

By regulation of the inflowing fuel, which regulation may be automatically controlled if so desired, the resultant fire when the burner is in normal operation may be low and function as a pilot fire or may have a greater degree varying from low to maximum or high fire at which time most if not all of the visible flame will lie above the top of the receptacle 17. At low fire, combustion will occur near the bottom of the receptacle 17 due to the fact that the air flowing through the lowermost row of apertures is sufficient to support combustion of the generated fuel gas where as at higher stages of fire where resultant combustion is raised, air flowing through the lowermost or lower rows of apertures may be termed primary air in that it is insufficient in quantity to support combustion, and therefore mixes or combines with the fuel gas to form a combustible mixture which is later burned by air from higher rows of apertures which may be termed secondary air. For example, at maximum or high flame all of the aspirating air may be primary air, the visible combustion being effected by secondary air flowing through the

apertures 28, which, being directed radially outward, tend to flatten the flame as well as to mix with the combustible gas.

We claim:

- 5 1. An oil burning heater comprising a burner receptacle, a central air inlet opening and a fuel inlet in the bottom thereof, a perforated sleeve extending upwardly from the opening and closed at the top, a correspondingly perforated shell surrounding the sleeve to form a fuel mixing space open at the bottom to the receptacle, means at the top of the shell for closing the space, the sleeve having openings above the top of the shell to supply secondary air at the top of the receptacle.
- 10 2. An oil burning heater in accordance with claim 1, in which the sleeve is closed by a plate at the upper end which extends outwardly to form a deflector substantially the width of the shell for directing secondary air outwardly from the top of the sleeve into the space at the top of the receptacle.
- 15 3. A ring-shaped burner comprising an open pot with imperforate walls and a central air opening, and means comprising a pair of spaced members provided with aligned apertures and in communication with said opening forming a central fuel inspirator in the pot extending upwardly from the opening with a fuel mixing chamber between said members open to the pot at the bottom to receive vaporized gas therefrom and to inject said gas therefrom outwardly in the pot.
- 20 4. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 25 5. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 30 6. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 35 7. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 40 8. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 45 9. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 50 10. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 55 11. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 60 12. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 65 13. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 70 14. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.
- 75 15. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell.

said receptacle outwardly of said shell, and means to deliver air unmixed with gas radially outward for admixture with the gases from said receptacle.

7. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from interior of said sleeve through said chamber into said receptacle whereby fuel vapor will be induced into said chamber for admixture with said air, the resultant mixture being directed into said receptacle outwardly of said shell, and means to deliver air unmixed with gas radially outward for admixture with the gases from said receptacle, said last named means comprising an extended portion of said sleeve provided with outwardly directed apertures.

8. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell, means to deliver air unmixed with gas radially outward for admixture with the gases from said receptacle, said last named means comprising an extended portion of said sleeve provided with outwardly directed apertures and a deflector member located above said last named apertures.

9. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture

with said air, the resultant mixture being directed into said receptacle outwardly of said shell and means extending outwardly from the sleeve above openings therein to obstruct the upward flow of gases from the perforations therebelow.

10. An oil burning heater comprising a receptacle with a bottom air opening and means to supply fuel to said receptacle, a perforated sleeve extending upwardly from said opening, a perforated shell surrounding said sleeve and spaced therefrom to form a chamber open at the bottom for communication with said receptacle, the perforations in said sleeve and shell being arranged in alignment to direct aspirating jets from the interior of said sleeve through said chamber into said receptacle whereby fuel vapor will be induced into said chamber for admixture with said air, the resultant mixture being directed into said receptacle outwardly of said shell, means extending between said sleeve and shell adjacent the top thereon to close said chamber at the top and means to direct air into said receptacle above said chamber.

11. An oil burning heater comprising a receptacle with a bottom air opening and means to supply fuel to the said receptacle, a perforated sleeve extending upwardly from said opening, a perforated shell surrounding said sleeve and spaced therefrom to form a chamber open at the bottom for communication with said receptacle, means to close said chamber at the top thereon, perforations in said sleeve and shell being arranged in alignment to direct aspirating jets from the interior of said sleeve through said chamber into said receptacle whereby fuel vapor will be induced into said chamber for admixture with said air and the resultant mixture directed into said receptacle outwardly of said sleeve, said apertures being arranged in substantially horizontal rows.

12. An oil burning heater comprising an open pot with imperforate walls and a central air opening, a central fuel inspirator in the pot extending upwardly from the opening constituting a fuel mixing chamber being open to the pot at the bottom to receive vaporized oil gas from said pot, said inspirator comprising spaced walls one within the other, each provided with aligned perforations operable to effect inspiration of the vaporized gas into said mixing chamber and therefrom into said pot by flow of air from said central air opening through said apertures.
